U.S. Cl. D14—27

FIGURE 1 is a side elevational view of a stanchion for a luggage rack showing my new design;

FIGURES 2, 3, and 4 are plan, rear elevational and front elevational views thereof, respectively;

FIGURE 5 is a side elevational view thereof illustrating the opposite side from that shown in FIGURE 1;

FIGURE 6 is a reduced scale perspective view thereof;

FIGURE 7 is a side elevational view of a stanchion for a luggage rack showing a modification of my new design;

FIGURES 8, 9, and 10 are plan, rear elevational and front elevational views of the form of my design illustrated in FIGURE 7;

FIGURE 11 is a side elevational view of the form of my design shown in FIGURE 7, looking from the opposite side; and

FIGURE 12 is a reduced scale perspective view of the form of my design shown in FIGURES 7-11.

The fragmentary part shown in broken lines in FIGURES 8, 9, 10, and 12 represents a cross bar adapted to be used with the stanchion and it is included for illustration purposes only.

I claim:

The ornamental design for a stanchion for a luggage rack, substantially as shown and described.
